SKIRT GUARDER

Ann M. Brown, Fort Huachuca, Ariz.
(P.O. Box 282, Seaboard, N.C.)
Filed Nov. 8, 1960, Ser. No. 68,007
4 Claims. (Cl. 2—304)

The present invention relates to a skirt guarder, and has particular reference to an improved device that maintains or holds a skirt or similar garment being worn from being blown upwards when the wind is blowing.

An outstanding advantage of the new skirt guarder resides in the feature that it is neither noticed by others in normal appearance as being worn at all, nor, is its presence conscious to the wearer that it is being worn, which features are due to its improved construction and simplicity in application and use. The embodiments of the invention readily stand the test of extreme windy conditions wherein the slip and the skirt of the wearer stay in their relative positions.

Another advantage of the new device resides in the substantially small expense in manufacturing the device. Each component of the device is made from the elastic or strong lace material except for the metal clips attached to the ends of the elastic or lace material, and include the garters which fit around the leg which are of any conventional construction. In applying the device, the wearer merely puts on the garters which fit around the legs in a conventional manner, and then applies the metal clips at the ends of the elastic or lace material to the seams adjacent thereto of the slip and also the skirt to hold and maintain the slip and the skirt respectively and substantially in place.

The construction of the skirt garter according to the invention may be made of plain material or of generally lace material to achieve a dainty effect, and the skirt garter may be made in any choice of colors.

One of the most important applications of the new device is in doing away for ever with the terrible embarrassment of having one's skirt go skyward during a heavy wind and while in the company of others. It has been found that it takes less than one minute to step into or put on the garters and attach each metal clip to its proper and respective portion of apparel.

Another advantage of the new device is that even when there are no seams to which the metal clips may be attached, the metal clips may be used effectively by attaching to corresponding locations of the slip and skirt without detracting from the appearance of the apparel.

Other objects and advantages will be apparent from a detailed description of the invention and from the appended drawings and claims.

In the drawings:

FIG. 1 is a diagrammatic cross sectional view in elevation of a slip and skirt having seams to which the device in accordance with the invention may be applied;

FIG. 2 is a plan view taken in cross section along lines 2—2 of FIG. 1, showing the preferred embodiment of the present invention;

FIG. 3 shows a simple metal clip that may be connected by a stitch operation to the ends of the elastic or lace material, into which the clip may be readily applied to the seams of the apparel, or to the apparel itself; and

FIG. 4 is a detailed plan view of the component parts of the invention laid out in one arrangement.

Referring now to the figures, a basic mechanical embodiment of the features of the present invention is shown in which there are two garters 10, 10 which extend around the leg in the usual fashion, and are either made adjustable or regular in size. Each of the garters

2

has sufficient material for attachment thereto by stitching or other connecting means or process, several extensions of elastic or lace material 12, 14, 16. Stitching or other connecting means including a metal clip (not shown) is provided between the garters and the respective ends of elastic or lace material 18, 20, 22. The elastic material may be of conventional one-eighth inch width and three to five or seven inches in length, in general terms, they may comprise of correspondingly sized and similarly characterized in strength, of lace or other material such as plastic or nylon construction. The elastic material 12 may be of one piece extending from one garter to the other with a metal clip 24 fastened or secured by stitching or other and equivalent methods to the center portion of the elastic material 12, or elastic material 12 may comprise of two pieces or segments extending from each garter and connected at the ends thereof by the metal clip 24, although this is not the preferred form of the invention.

20 The metal clips 24, 24 as well as metal clips 26, 26 are each secured to a portion of the proximate seam of the slip; where there is no seam present at the proximate locations of the metal clips, the metal clips may be safely attached to the slip or the dress where desired to achieve the necessary results.

25 The metal clip may be of any of various well known forms, but the clip is preferably a clip that may have material stitched readily thereto, and may engage material securely by pressing the clip to open. Such clips are well known and extensively used in the dry cleaning industry to attach identification tags to garments.

30 It is further within the contemplation of the present invention to provide short two-inch, three-inch or four-inch strips having a metal clip attached to each end thereof, as shown in FIG. 4, for applying the metal clip to the seam or hem of the slip at one end and the hem or seam of the skirt at the other. Metal clips are of sufficient strength to withstand the tension subjected to forces created by strong winds so that under all conditions the skirt and the slip respectively are substantially held and maintained in their desired positions.

35 It is thus seen that there is provided a new and improved skirt guarder that does not provide any observable appearance to others not knowing whether the skirt guarder is being worn or not, and its presence is not substantially conscious to the wearer so that there is provided a securing means that maintains the skirt and slip secure under extreme windy conditions and thereby eliminating embarrassment by lack of control under such conditions.

40 A further advantage of the present invention resides in the ornamental characteristics and features of plain or dainty construction that may bring about a garter fad or era of substantial value among teenagers, adults and juniors.

45 55 Additional embodiments of the invention in this specification will occur to others and therefore, it is intended that the scope of the invention be limited only by the appended claims and not by the embodiments herein above described. Accordingly, reference should be made to the following claims in determining the full scope of the invention.

What is claimed is:

1. A skirt guarder improvement comprising a pair of garters each adapted for fitting around legs of a wearer, a plurality of material strips each secured to a peripheral portion of one of the garters adapted to extend exteriorly thereof, a metal clip at the end of each of the said material strips adapted to be secured to a seam proximate to the hem area of a slip, an additional plurality of material strips each adapted to be secured to a peripheral portion of the hem area of the slip by additional metal

clips at the end of said additional material strips, and a further metal clip at the end of each of the said additional material strips adapted to be secured to a seam proximate to the hem area of a skirt, wherein said skirt guarder provides necessary control of said slip and skirt from extending upwardly under conditions of severe wind.

2. A skirt guarder improvement according to claim 1 wherein said material is elastic.

3. A skirt guarder improvement according to claim 1 10 wherein said material is lace.

4. A skirt guarder improvement according to claim 1 wherein said metal clips are adapted to be secured to the material of the slip and skirt, respectively.
